US0D1075951S

(12) United States Design Patent (10) Patent No.: US D1,075,951 S
(45) Date of Patent:  *May 20, 2025

(54) TOY BLOCK

(71) Applicant: Laltitude LLC, Hacienda Heights, CA (US)

(72) Inventor: Howard Wang, Hacienda Heights, CA (US)

(73) Assignee: Laltitude LLC, Hacienda Heights, CA (US)

(*) Notice: This patent is subject to a terminal disclaimer.

() Term: 15 Years

(21) Appl. No.: 29/812,346

(22) Filed: Oct. 29, 2021

Related U.S. Application Data

(63) Continuation-in-part of application No. 17/141,073, filed on Jan. 4, 2021, now abandoned, which is a continuation of application No. 16/827,350, filed on Mar. 23, 2020, now Pat. No. 11,045,740.
